CARL BRUUN STRÖYBERG AND SØREN NIELSEN, OF ROSKILDE, AND CARL ELMER, OF NAURBJERG MEJERI, DENMARK.

APPARATUS FOR LIFTING AND EMPTYING PAILS AND CANS.

1,334,327.

Specification of Letters Patent. Patented Mar. 23, 1920.

Application filed August 7, 1917. Serial No. 184,931.

To all whom it may concern:

Be it known that we, CARL BRUUN STRÖYBERG and SØREN NIELSEN, residing at Roskilde, and CARL ELMER, residing at Naurbjerg Mejeri, Denmark, subjects of the King of Denmark, have invented certain new and useful Improvements in Apparatus for Lifting and Emptying Pails and Cans; and we do hereby declare the following to be a full, clear, and exact description of the invention.

Our invention refers to a continuously acting apparatus for lifting and emptying pails and cans, especially milk-cans.

One form of construction is shown in the drawing in Figs. 1, 2, and 3, front view, side view, and plan, respectively.

On a bed plate 4 there are disposed, firstly, a strap-shaped standard 5 the upper part of which is bent outward from the bed plate, serving as a rest for the upper part of the can or pail during the process of lifting and emptying; and, secondly, a standard 6, U-shaped in section, which serves to carry the transmission (countershaft) and to guide the lifting apparatus. The transmission consists of a pulley 7, a therewith connected worm 8, and a worm-wheel 9 disposed on the same shaft as the sprocket-wheel 10. A chain 12 runs over this latter and another, preferably adjustable, sprocket-wheel 11 disposed vertically below said sprocket-wheel 10. The lifting apparatus consists, firstly, of a carriage 13 with guide-rollers 14 on the outside of the standard 6, and, secondly, of a supporting-plate 15, which is turnably suspended at an intermediate point in unstable equilibrium on an axle-pin 16 on the side of the carriage 13 and has bent arms 17 with rollers 18 as support for the lower part of the can or pail. Between a pin 19, on one of the links 12 for the chain, and a pin 20, on the carriage 13, there is disposed a suitable transmission-member, which insures a certain free-run, for instance, a pliant traction-member or, as shown, a connecting-rod 21 with a slit 22 in which runs one of these pins, for instance, the pin 20.

When the supporting-plate 15 is in its lowermost position, it fits into a cavity, or recess, in the bed plate 4, so that its upper edge is flush with the upper edge of the bed

plate. The chain transmission is disposed in the hollow part of the standard 6.

As the chain-transmission is driven around in the direction of the arrow 24, and the pin 19 alternately goes up and down, the carriage 13 with the supporting-plate 15 will also alternately go up and down, but in such a manner that, owing to the slit 22, it will each time, for a short period, find itself at rest in the lowermost position, namely, as long as the connecting-rod 21 takes to pass from the left position (indicated by dashes and dots in Fig. 1) to the right position symmetrical with the left. This extended pause occurs only when the carriage is at the lower limit of its movement, as it is suspended at the upper limit of its movement, and the link does not move vertically independently of the carriage at such upper limit of the movement of the latter. At the lower limit of the movement of the carriage the link has a limited independent vertical movement, owing to the slot 22. During this period of time, the operator removes the empty pail or can from the supporting plate 15 and places a filled pail or can on it, so that it abuts against the bent arms 17. In this position the can and the supporting plate will have an overbalance to the left in Fig. 3 and will therefore, during its movement upward, tip toward this side, and the top part of the can will repose against and be guided by the standard 5. When the can approaches the emptying position (indicated by dotted lines in Fig. 3), it will also be supported by the rollers 18 on the bent arms 17.

We claim:

An apparatus for lifting and emptying receptacles including a carriage, mechanism for elevating and lowering the carriage, a tiltable platform pivoted at an intermediate point to the carriage in unstable equilibrium to effect an automatic tilting of a receptacle, and means coöperating with the platform for supporting the receptacle in emptying position.

In testimony that we claim the foregoing as our invention, we have signed our names.

CARL BRUUN STRÖYBERG.

SØREN NIELSEN.

CARL ELMER.
